UNITED STATES PATENT OFFICE.

EDWARD ALDOM, OF BROOKLYN, NEW YORK.

TOY CAP-EXPLoder.

SPECIFICATION forming part of Letters Patent No. 258,972, dated June 6, 1882.

Application filed January 20, 1882. (No model.)

To all whom it may concern:

Be it known that I, EDWARD ALDOM, of 392 South Fourth street, in the city of Brooklyn, in the county of Kings, and in the State of New York, have invented a new and useful Improvement 5 in a Toy Ball Cap-Exploder; and I do hereby declare that the following is a full, clear, and exact description of the invention.

My invention relates to improvements in 10 that class of toy cap-exploders which is so extensively used by children in celebrating the anniversary of the Day of Independence.

The object of my invention is to give the children a cheap and safe cap-exploder.

15 Figure 1 represents the ball after the cap has been exploded. Fig. 2 is a sectional view of the cap-exploder. Fig. 3 is a side view, showing the slot cut in ball.

I construct the exploder as shown in Fig. 2. 20 A is the hammer. B is the spring. C is the rivet, and D is the nipple upon which the cap is exploded. E is a hole, to which the string is attached.

The ball is made of wood, papier-maché, 25 metal, or other suitable material.

The cap can be exploded with or without the spring attached.

To use the invention, I attach a string to the

bottom of the hammer, as shown in Fig. 1. By holding the string in one hand and having 30 previously placed a cap in the place provided and cocked the hammer, you throw the ball from you, retaining your hold on the string. By the sudden jerk backward the hammer is relieved and the cap is exploded. It can also 35 be used by two children in the following manner, viz: An extra string can be attached to the opposite side of the ball in the eye provided for it, as shown in Fig. 2, F. Each child taking an end, the exploder will then be in the 40 center. By each pulling at the same time the cap is exploded, thereby rendering it a cheap, safe, and amusing toy.

What I claim as my invention, and desire to 45 secure by Letters Patent, is—

A ball with a slot cut half-way through to the center, in combination with hammer A, pivoted in said slot, and spring B, bearing upon the hammer, with a string attached to the lower part of hammer, at E, combined and arranged 50 to operate substantially as and for the purpose set forth.

EDWARD ALDOM.
